CLAIM

I claim the ornamental design for a knitting needle bundling device, as shown.

DESCRIPTION

FIG. 1 is a front view of a knitting needle bundling device showing my new design;

FIG. 2 is a rear view of the same bundling device;

FIG. 3 is a left side view of the same bundling device;

FIG. 4 is a right side view of the same bundling device;

FIG. 5 is a top plan view of the same bundling device; and,

FIG. 6 is a bottom view of the same bundling device.
